UNITED STATES PATENT OFFICE.

ELMER C. POOL, OF NEW CASTLE, PENNSYLVANIA.

AUTOMATIC FEED FOR TINNING MACHINES.

Application filed November 26, 1920. Serial No. 426,627.

To all whom it may concern:

Be it known that I, ELMER C. POOL, a citizen of the United States, and resident of New Castle, in the county of Lawrence and State of Pennsylvania, have invented certain new and useful Improvements in Automatic Feeds for Tinning Machines, of which the following is a specification.

My invention relates to the manipulation of sheet metal plates, and more particularly to the feeding of such plates, one at a time, from a pile to a tinning machine, and has for one of its objects the producing of an improved feeding mechanism whereby adhesive means such as a magnetic force will be employed to lift the plates, one at a time, from a pile, without moving more than one plate, and without disturbing the position of the plate or plates next to the one being removed.

Another object is to provide improved safety means for preventing more than one plate being carried or fed into the tinning machine.

Still another object is to provide means for automatically diverting two or more overlapping plates out of the machine before they enter the tinning pot, should the first safety means fail to separate such plates.

While my invention is primarily designed for use in delivering plates to tinning machines, and is illustrated in connection with such a machine, the invention is not limited thereto, but may be employed in various other combinations where it is desired to manipulate plates, one at a time, without danger of carrying more than one.

The primary feature of my invention is to provide a machine with a rotary plate moving magnetic member, having a plurality of diametrically disposed poles around its periphery, adapted to contact with the face of the outermost plate, and to so spread the path of the magnetic lines or circuit over the plate that there is no tendency for any of the magnetic lines to pass therethrough into the next adjacent plate or plates, such terminals or poles being of such form as to concentrate the lines of force into a relatively small area when entering the plate, thereby increasing the pull or holding power of the magnet.

The above and other objects and advantages will be more fully brought out in the following specification and claims, and will

be fully illustrated in the accompanying drawings, in which—

Figure 1 is a sectional side elevation of the device.

Figure 2 is a top plan thereof. 60

Figure 3 is a rear elevation thereof.

Figure 4 is a side elevation showing the drive connections.

Figure 5 is an enlarged fragmentary detailed view showing the magnetic feed roller, 65 magnetic plate separator, plate guides, and other associated parts.

Figure 6 is an enlarged detail view of the magnetic feed roller, partly in section.

Figure 7 is an enlarged detail view of the 70 magnetic plate separator.

In the accompanying drawings, the letter A designates a tinning pot, in itself an old and approved form. The pot is separated transversely by a vertical wall or partition 75 2, into compartments B and C. The lower edge of this partition or septum 2 which terminates above the bottom of the tinning pot, and the upper edge of a rib or projection 3 on the bottom of the pot defines 80 the width or vertical dimension of a narrow passage or opening D, through which the plates, while submerged in the bath of molten tin, pass from the compartment B into the compartment C of the pot A. The 85 particular pot shown is of a width which permits of two or more plates, side by side, being passed through the tinning pot.

Located immediately above the upper edge of the compartment B, at the plate 90 entering side of the tinning pot, are two sets of feed rollers E and F, which are arranged to receive the plates from my improved feeding mechanism to be described, and to move them forwardly and downwardly into the tin pot at an angle to the horizontal. 95

The feed rollers F are at a somewhat lower level than the rollers E, and an adjustable roller G is located on the discharge 100 side of the set F to guide and direct the front end of the successive plates forwardly and downwardly, into the molten tin in compartment B, as they emerge from between the rollers F. 105

Positioned within the compartment B, closely adjacent to the passage D, is a set of pressure rolls I. These pressure rolls feed the plates from compartment B into the compartment C. 110

Two sets of feed-out rollers J and K are provided in the compartment C of pot A to feed-out the plates and also to squeeze off surplus tin from the plates.

5 An inclined apron plate 10 is provided at the entrance end of the compartment B of the pot to receive the plates as they are delivered from my improved feeding mechanism. Other guide plates 12 and 13, 10 are arranged to guide the plates through the rolls F and I, and curved guide plates 14 and 14' form a guide N which directs the forward end of the plates emerging from the set of pressure rolls I upwardly 15 into the bite of the lower set J of the feed-out rollers J and K.

My improved feeding mechanism is adapted to be located directly to the rear of the tinning pot and comprises a double 20 set of parts arranged side by side so as to act on two piles of plates at one time, thereby feeding two plates, side by side, into the tinning machine.

A framework or supporting structure 16 25 is secured to and extends rearwardly from the tinning pot A and supports the several parts comprising my feeding mechanism. A bosh or receptacle 17 is secured to and extends below the framework 16 and is 30 adapted to retain a vertically adjustable plate pile holder. The plate holder comprises a back rest member 19 which is secured to the back wall of the bosh 17 and projects inwardly and downwardly at an 35 angle, so as to slidably support an L-shaped plate retainer 20 which is of sufficient width to hold two piles of plates side by side. The plate retainer 20 is adjustably held in position and adapted to be vertically adjusted by means of a pair of chains 21, one 40 of which is secured on each end thereof and passed upwardly over suitable sheaves 22 splined on a shaft 23 journaled in the bosh this shaft having a ratchet and dog operating mechanism 24 on one end outside 45 of the end wall of the bosh.

Mounted on the rear edge of the supporting framework 16 at each end and center thereof is a bracket 25 supporting a 50 shaft 26, having four arms 27 loosely mounted thereon for pivotal movement.

The arms 27 have a pair of cylindrical magnetic plate lifters Y journaled and supported in their lower ends, and the center 55 arms have their upper ends counterweighted by adjustable counterweights 29 mounted on a projecting arm 30. A locking lever 31 is pivoted on the arms 27, having the counterweights adjacent their upper ends, 60 and such lever is provided with a notch 32 to engage with the projecting tongue 33 on the frame 16 so as to hold the magnetic plate lifters Y out of their plate engaging position when desired.

The magnetic plate lifters Y, each com-

prises a permanent magnetic member 34 mounted within a pair of hollow cylindrical casings 35 which have their inner ends spaced apart and joined by a non-magnetic hollow cylindrical tubular member 36. Stub 70 shafts 37 are threaded into the outer ends of the casings 35 and support the whole structure in suitable bearings formed in the lower ends of the arms 27.

The hollow cylindrical casing members 35 75 are formed from soft iron or other material which will readily convey the circuit or attracting forces from the permanent magnet 34, thus forming unlike poles through which a circuit will be completed when they contact with a plate.

The outer surface or periphery of the members 35 is fluted, forming a series of knife edge ribs or projections 39. It will thus be seen that each of the ribs or projections 39 will successively engage a plate as the magnet is rotated, and that projections on the opposite casings will form opposite or unlike pole contacts, and that such projections will contact with the face of the 90 outermost plate of the pile in the retainer 20. The effect of the knife edge contacts will be to concentrate the forces of the magnet in the immediate plate and prevent the spreading of the forces through and into 95 the next adjoining plates.

Suitable cross-beams 40-40' are arranged to extend from one end of the frame support 16 to the other immediately above the upper edge of the bosh, and carry suitable 100 curved guide strips 41-42 arranged to form an upwardly and inwardly inclined passage-way to guide the plates being conveyed.

A second pair of cross-beams 43-43' are arranged forward of and above the cross-beams 40, and carry other guide strips 44-45 forming a second passage-way adapted to receive the plates from the passage-way between the strips 41-42, and direct them forwardly and upwardly between suitable pinch rollers 46 and 47 which may be of any well-known construction.

The lower one of the pair of pinch rollers E is driven by a suitable source of power and carries a sprocket 48 on each end. The 115 pinch roller 46 also carries a sprocket 48^a on each end in line with the sprocket 48, and a third sprocket 48^b is mounted on each end of the shaft 26 in line with the sprockets 48 and 48^a. A link chain 49 is trained about 120 the sprockets 48, 48^a, 48^b, thus driving the pinch rollers E, pinch rollers 46 and 47, and shaft 26 at the same speed. It will be understood that if found desirable in practice, a single set of drive sprockets may be used.

A pair of sprockets 50 of somewhat smaller diameter than the sprockets 48, 48^a, 48^b are mounted on the ends of the shaft 26, and a sprocket 51, of greater diameter than sprockets 50, is mounted on the end of the 130

outside stub shaft 37 of each magnetic conveyer, and a link chain 52 is trained over the sprockets 50 and 51 to constantly drive the conveyer members, which will necessarily revolve at a lesser speed than the pinch rollers E and pinch rollers 46, 47, due to the difference in size of the sprockets 50 and 51.

A cross-beam member 54 is arranged forward of the rollers 46-47 and has two pairs 10 of suitably spaced depending lugs 55 which support pivot shafts 56 adapted to have hinged guide plates 57 supported thereon. Plates 57 have a crank arm 58 secured thereto which abuts the cross-beam 54 when the 15 plate is in its lowermost position, and carries a counterweighted lever 59 to normally hold it in such position.

Supported on suitable cross-beams 60 forward of the hinged plates 57, and in proximity thereto, is a pair of guide plates 61. The plates 61 are formed of top and bottom pointed portions, the top portion being directed forwardly over the rollers E and the bottom portion directed downwardly and 25 forwardly to the passage between the rollers E.

The inclined apron 10 of the tinning pot is arranged below the plates 57 and 61, and completes the passage-way to the rollers E.

The hinged counterweighted guide plates 57 serve as a trap so that if more than one plate or sheet should be carried through the pinch rollers 46-47 they will bear against the guide plate 57 with sufficient force to 35 counteract the effect of the counterweighted lever 59 and raise the guide plate, thereby allowing the plurality of plates or sheets to pass over the dual guide plates 61 and away from the tinning pot.

Magnetic separators X are mounted above each of the magnetic plate lifters Y and comprise a rectangular casing member 63 pivotally supported on the cross-beam 40. The casings 63 contain a permanent magnet 64 and are provided with blade or knife edge poles 65 which extend into the path of the lifted plates and contacts with the rear faces thereof. The magnet 64 is of less strength than the magnets of the plate lifter 50 Y, and, therefore, will not materially retard the movement of the plates, yet it is of sufficient strength that if two plates should stick or in some manner be lifted together, it will retard the movement of the second plate, 55 and thus separate them.

A still further means for preventing the feeding of more than a single plate into the tinning pot is located just to the rear of the pinch rollers 46-47, and comprises a shaft 67 journaled in the frame support 16 and having a plurality of locking fingers 68 of triangular shape, secured thereon and of such size that their flat sides will extend past the guide strips and into the path of the 65 lifted plates. As the plates are guided be-

tween the strips 44 and 45, they will bear against the upper strips 44 due to the direction of their travel, and in this position they will strike the fingers 68 and cause the shaft and fingers to rotate one-third of a revolution, thereby presenting one of the other faces of the fingers against the plate. If a second plate is overlapped on the first in such a manner that its forward edge is disposed to the rear of the forward edge of the 70 first plate, it will strike the fingers and be held, since the fingers can not again rotate until the first plate has passed from under and clears the fingers.

Another feature and function of these fingers is that they will cause an even feed of the plates from both of the magnetic feed rollers Y, since if one roller feeds a plate in advance of the other, the first to reach or strike the fingers 68 will rotate them the one-third turn, and then lock them against rotation until it has passed from thereunder, and the plate that is in the rear will be held until the fingers are again freed when another plate will be presented by the other 80 magnetic feed roller to follow the one just clearing the fingers, thus causing the newly presented plate, and the held plate to pass together to the rollers 46-47.

The operation of my improved feeding mechanism will be readily understood from the above description taken with the accompanying drawings. The peculiar and novel construction of magnetic plate lift will cause the magnetic forces to be concentrated on a single plate of the pile and will lift it through the guide passages to the pinch rollers 46-47, which will in turn feed it to the pinch rollers E of the tinning pot.

The operations of the three separate mechanisms for preventing more than one plate being carried to the tinning pot, have also been fully described above, and will not be gone into again, although these mechanisms are important features and are distinct improvements over any devices heretofore known.

It will be readily understood that while I have described my invention in combination with a tinning pot, it is not limited to 115 such use, but may be used wherever it is desired to feed single plates, and therefore I do not wish to be limited to such a combination.

It will also be understood that while I 120 have shown and described one embodiment of my invention with great particularity, I do not wish nor do I intend to limit my invention to such structure, since various modifications in structures and combination of parts may be made without departing from the spirit of my invention as defined in the appended claims. For instance, wound active magnets may be substituted for the permanent magnets shown, a rotat-

ing roller having a series of vacuum cups on the periphery thereof forming adhesive means for engaging the plates may be used instead of the magnets, or other such substitutions of equivalents made as found necessary or desirable.

It will also be further understood that this apparatus may be used to feed plates from a horizontal pile. That is, the plates 10 may be moved longitudinally or sideways from a horizontal pile, and the words lifted or lifting, as used in the several claims will be understood to include this movement.

I claim:—

15. 1. An automatic plate feeder, including a cylindrical rotary magnetic lifter member having opposite pole portions adapted to contact with a plate and complete the magnetic circuit therethrough, said pole portions 20 having their outer peripheries fluted, forming knife edge contacting surfaces.
2. An automatic plate feeder for lifting and feeding single plates from a pile in facewise engagement, one with the other, 25 comprising a rotary magnet having a plurality of radial knife edge poles around its periphery and adapted to successively engage the exposed face of the outermost plate as the magnet is rotated, said magnet operating 30 to move plates one by one from said pile.
3. The combination with a tinning pot of an automatic plate feeder, said feeder comprising a rotary magnetic member, said member having a plurality of poles adapted 35 to successively engage plates fed thereby and said poles being arranged in aligned pairs of positive and negative poles.
4. The combination with a tinning pot, of a rotary magnet having a plurality of 40 knife edge poles spaced around its periphery, said magnet operating to move plates one by one from a pile in which the plates bear one against the other.
5. The combination with a tinning ma- 45 chine for tinning metal plates, and a support for a pile of plates to be delivered to the machine with the plates of the pile in facewise engagement one with the other, of a rotary magnet having a plurality of knife 50 edge poles disposed diametrically around its periphery and adapted to successively engage the exposed face of the outermost plate as the magnet is rotated, said magnet operating 55 to move plates one by one from said pile.
6. The combination with a tinning ma- 60 chine for tinning metal plates, and a support for a pile of plates to be delivered to the machine with the plates of the pile in facewise engagement one with the other, of a rotary magnet having a plurality of knife 65 edge poles disposed diametrically around its periphery and adapted to successively engage the exposed face of the outermost plate as the magnet is rotated, said magnet

operating to move plates one by one from said pile, and a second magnet of less strength than said first named magnet extending into the path of the plate being moved and adapted to yieldably engage the 70 opposite face from that engaged by said first named magnet and to exert a counter-pull thereon, said magnet being of such strength as to not materially retard the movement of the plate, but being sufficient 75 to hold back a second plate if two be stuck and so moved from the pile together.

7. The combination with a tinning pot for tinning metal plates, and suitable plate guideways arranged therein, of a pair of 80 feeding rollers arranged at the entrance end of said guideways, and a rotatable magnetic member, said magnetic member having a fluted periphery forming knife edge contacting surfaces adapted to engage the 85 outermost plate of a pile and move it upwardly into engagement with said feed rollers.

8. The combination with a tinning pot for tinning metal plates, having suitable 90 guideways arranged therein, of a pair of feeding rollers arranged at the entrance end of said guideways, other guideways to the rear of and extending below said feed rollers, and a rotatable magnetic member having a plurality of knife edge poles adapted 95 to successively engage the outermost plate of a pile and move it upwardly through said last named guideways, into engagement with said feed rollers.

9. The combination with a tinning pot for tinning metal plates, having suitable guideways arranged therein, of a pair of feeding rollers arranged at the entrance end of said guideways, other guideways to the 105 rear of and extending below said feed rollers, a rotary magnet having a plurality of knife edge poles disposed diametrically around its periphery and adapted to successively engage the exposed face of the 110 outermost plate of a pile as said magnet is rotated, said magnet operating to move the plates one by one from the pile up through said last named guideways, and into engagement with said feed rolls, and a second mag- 115 net of less strength than said first named magnet extending into the path of the plate as it is moved upwardly between said last named guideways and adapted to yieldably engage the opposite face from that engaged 120 by said first named magnet and to exert a counter-pull thereon, said magnet being of such strength as not to materially retard the movement of the plate, but being sufficient to hold back a second plate if two be stuck 125 together.

10. The combination with a tinning pot for tinning metal plates, having suitable guideways arranged therein, of a pair of feeding rollers arranged at the entrance end 130

- of said guideways, other guideways to the rear of and extending below said feed rollers, and a rotatable magnet member having a plurality of knife edge poles adapted to 5 successively engage the outermost plate of a pile and move it upwardly through said last named guideways into engagement with said feed rollers, and means to prevent overlapping plates entering said feed rolls, said 10 means comprising stop members adapted to be actuated by the first plate and moved down so as to engage and hold a second overlapping plate until said first plate has passed into the rolls.
11. The combination with a tinning pot for tinning metal plates, having suitable guideways arranged therein, of a pair of feeding rollers arranged at the entrance end of said guideways, other guideways to the 15 rear of and extending below said feed rollers, and a rotatable magnetic member having a plurality of knife edge poles adapted to successively engage the outermost plate of a pile and move it upwardly through said last named guideways into engagement with said feed rollers, and means for preventing the passage of two or more overlapping or stuck plates through said first named guideways, said means comprising a 20 weighted trap located at a curve in said guideways, the tension of a single plate being insufficient to operate such trap while the tension of two or more plates will cause it to operate and divert the plates.
12. The combination with a tinning machine for tinning plates, having suitable guideways arranged therein, and a vertically adjustable support for a pile of plates to be delivered to the machine with the 25 plates of the pile in facewise engagement one with the other, of a pair of feeding rollers arranged at the entrance end of said guideways, other guideways to the rear of and extending below said feed rollers, and a 30 rotatable magnetic member having a plurality of knife edge poles adapted to successively engage the outermost plate of said pile and move it upwardly through said last named guideways into engagement with 35 said feed rollers.
13. The combination with a tinning machine for tinning plates having suitable guideways arranged therein, and a vertically adjustable support for a pile of plates to be delivered to the machine with the plates of the pile in facewise engagement one with the other, of a pair of feeding rollers arranged at the entrance end of said guideways, other guideways to the rear of and 40 extending below said feed rollers, a rotary magnetic member mounted below said last named guideways and adapted to engage the pile of plates on said support, said magnet having a plurality of knife edge poles disposed 45 diametrically around its periphery adapted to successively engage the exposed face of the outermost plate of the pile as said member is rotated, said member operating to move the plates, one by one, from the pile up through said last named guideways and into engagement with said feed rollers, and means for preventing the passage of two or 50 more overlapping or stuck plates through said first named guideways, said means comprising a weighted trap forming a curved portion of said first named guideways, the tension of a single sheet plate as it passes through said curved portion of said guideway being insufficient to operate said trap, while the tension of two or more plates will cause said trap to operate and divert the plates.
14. The combination with a tinning machine for tinning plates, having suitable guideways arranged therein, and a vertically adjustable support for a pile of plates to be delivered to the machine with the plates of the pile in facewise engagement one with the other, of a pair of feeding rollers arranged at the entrance end of said guideways, other guideways to the rear of and extending below said feed rollers, a rotary magnetic member mounted below said last named guideways and adapted to yieldingly engage the opposite face from that engaged by said first named magnet and to exert a counter-pull thereon, said magnet being of such strength as not to materially retard the movement of a single plate but being sufficient to hold back a second plate if two be stuck together.
15. An automatic plate feeder, comprising pinch rollers, guideways and magnetic means for feeding not more than one plate at a time from the pile.
16. An automatic plate feeder, comprising a cylindrical rotary magnetic feeder member having opposite pole portions adapted to contact with a plate and complete the magnetic circuit therethrough, in combination with suitable guideways.
17. An automatic plate feeder, including a cylindrical rotary magnetic feeder member having opposite pole portions adapted to contact with a plate and complete the magnetic circuit therethrough, said pole por-

tions having their outer peripheries fluted, forming knife edge contacting surfaces.

18. An automatic plate feeder for feeding single plates from a pile in facewise engagement, one with the other, comprising a rotary magnet having a plurality of radial knife edge poles around its periphery and adapted to successively engage the exposed face of the outermost plate as the magnet is rotated, said magnet operating to move plates one by one from said pile.

19. The combination with a tipping pot and feed rollers adapted to feed plates successively into and through said tipping pot

at a uniform speed, of plate feeding means 15 for delivering plates into said tipping pot, said feeding means including pinch rollers and a rotary plate feeding member adapted to engage and feed successive plates into the bite of said pinch rollers, said feeding means 20 being arranged to adhere to the plate brought into contact therewith in delivering the plate to said pinch rollers and means for turning said feeding member in the plate feeding operations.

In testimony whereof I have hereunto signed my name.

ELMER C. POOL.
